CLAIM

The ornamental design for a case for mobile phone, as shown and described.

DESCRIPTION

FIG. 1 is a front perspective view of a case for mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is another front perspective view thereof depicting the case for mobile phone in a standing configuration; and, FIG. 10 is a cross-sectional view taken along line 10-10 in FIG. 2.

The evenly-spaced dashed broken lines in the figures depict portions of the case for mobile phone that form no part of the claimed design.

1 Claim, 9 Drawing Sheets
